CIRCUIT BREAKER

John G. Jackson, Detroit, Mich., assignor to
 Square D Company, Detroit, Mich., a corpora-
 tion of Michigan

Application September 27, 1947, Serial No. 776,528

22 Claims. (Cl. 200—88)

1

This invention relates to automatic electric circuit breakers and more particularly to current responsive tripping means for effecting the automatic opening of such circuit breakers upon current overload.

One object of the invention is to provide a simple and economical but effective combined thermal and magnetic tripping means for an automatic electric circuit breaker.

Another object of the invention is to provide tripping means for an automatic electric circuit breaker including a current responsive bimetallic member adapted to flex upon moderate current overload to effect opening of the circuit breaker, with relatively stationary and movable magnetic elements for effecting magnetic tripping of the circuit breaker on heavy current overloads and short circuits and with the magnetic elements bodily supported upon the bimetallic member.

Another object of the invention is to provide tripping means in accordance with the preceding object in which the movable magnetic member moves a resilient latching tip which is also mounted upon the bimetallic member so as to be bodily movable therewith upon thermal trip as well as movable relative thereto upon magnetic trip.

Another object of the invention is to provide a tripping means in accordance with the immediately preceding object in which an integral extension of the resilient latching tip serves to mount the movable magnetic member upon the bimetallic member.

Another object of the invention is to provide tripping means for an automatic electric circuit breaker having relatively stationary and movable magnetic members in which the movable magnetic member rotates about an edge on the stationary magnetic member to effect the magnetic tripping of the circuit breaker and in which the movable magnetic member is maintained in contact with the stationary magnetic member edge to minimize the reluctance of the flux path theret.

Other objects and features of the invention will be readily apparent to those skilled in the art from the specification and appended drawings illustrating certain preferred embodiments in which:

Figure 1 is a front elevational view of a circuit breaker according to the present invention with the front cover broken away over the current responsive tripping means.

Figure 2 is a vertical sectional view on the line II—II of Figure 1 and showing the breaker mechanism in the off position.

2

Figure 3 is a bottom plan view of the current responsive tripping means when in the position of Figure 1 but with the movable armature removed.

5 Figure 4 is a detail sectional view on the line IV—IV of Figure 3.

Figure 5 is a sectional view through the current responsive tripping means taken on the line V—V of Figure 3.

10 Figure 6 is a view of the armature member alone taken in bottom plan from the position of Figure 1.

The current responsive tripping means of this invention has been illustrated in connection with 15 a circuit breaker mechanism which will be but briefly described, with more particular reference to Figure 2, and which comprises an insulating base 1 having a conducting strap 2 mounted on an end ledge of the base by means of a hollow spun over rivet 3 in which is threaded a terminal stud 4. The conducting strap 2 extends within the hollow portion of the base 1 through an end opening which is closed by means of an insulating plate 5, the interior end of conducting 20 strap 2 carrying a stationary contact 13. Guided within the base for rectilinear movement toward and away from the back of the base is a generally U-shaped member 6 having a flat forward surface 7 which cooperates with an interior camming surface upon a manually operable handle 8 mounted for pivotal movement upon integral shaft 9. Upon the longer leg of the element 6 is pivotally mounted, by interengaging notches, a contact bar 11 carrying at one end a movable contact 12 cooperating with the stationary contact 13. A compression spring 14 is disposed 25 between the bottom of the base and the contact bar 11 so as to bias the bar away from the bottom of the base and for rotation about its engagement with the element 6.

Upon an end ledge at the end of the base opposite to the conducting strap 2 is mounted a second conducting strap 15 by means of a hollow spun over rivet 16 into which is threaded a terminal screw 12. The conducting strap 15 extends within the base 1 through an end opening closed by an insulating plate 18 and has a pressed out central portion 19 at its interior end upon which is mounted a bimetallic member 21. Between the pressed out portion 19 of the conducting strap 15 and the normal legs 22 thereof is disposed an element 23 within which is threaded a stud 24 which is movable to bend the pressed out portion 19 to effect thermal calibration of the breaker. Sealing material to prevent access to the stud 24 after calibration is indicated at 25.

The current responsive tripping means according to the present invention will be described more in detail in connection with the other figures of the drawing, and will be herein referred to only briefly as comprising a stationary magnetic yoke 26, a magnetic armature 27 and a resilient latching tip 28 mounted upon the bimetallic member 21 and movable bodily therewith and relative thereto. A conducting flexible lead 30 interconnects the bimetallic member 21 and the contact bar 11.

In the operation of the breaker mechanism of Figure 2 the parts are shown in manually disengaged position. If the handle 8 is rotated in a counterclockwise direction, a cam surface of lesser diameter will be presented to the surface 7 of the rectilinearly movable element 6 so that this element will be moved forwardly of the breaker under the action of spring 14. In this movement, the contact bar 11 will pivot about its engagement with the latching tip 28 until contact 12 engages contact 13 to complete the circuit through the breaker. For return to the manually off position, the handle is rotated in a clockwise direction and the parts then reassume the position of Figure 2.

With the contacts engaged, upon the occurrence of a moderate overload through the circuit breaker the bimetallic member 21 will be heated by the passage of current therethrough and will flex in a clockwise direction to bodily move the latching tip 28 off of the latching end of the contact bar 11 which then rotates about its pivotal mounting upon the longer leg of the element 6, under the bias of spring 14 and in a clockwise direction, to move contact 12 to disengaged position. To reset the parts after an automatic operation, the handle 8 is rotated in a clockwise direction beyond the off position whereupon the element 6 in moving toward the back of the breaker will effect rotation of the contact bar 11, as well as movement bodily thereof, so that the contact bar rotates in a counterclockwise direction to again place its latching end in back of the latching tip 28. After resetting, movement of the operating handle in a counterclockwise direction will again engage the contacts to close the circuit through the breaker.

The tripping magnetically is effected upon the occurrence of heavy overloads or short circuits wherein the armature is attracted to the yoke 26 in a shorter time than would be required for the heating and flexing of the bimetallic member 21. In magnetic tripping the armature 27, when attracted to the yoke 26, engages the resilient latching tip 28 to move it relative to the bimetallic member 21 to effect unlatching of the contact bar 11 and hence rotation thereof to the contacts disengaged position.

The construction of applicant's new current responsive tripping means is shown more particularly with reference to Figures 3 through 6. The resilient latching tip 28 is formed on a spring member 29 having an upper hook portion 31 which extends through a slot 32 in the armature 27 to mount the armature upon the bimetallic member 21. The latching tip 28 is provided with a projecting nose as shown and has a flange 33 at its back end which engages the bimetal 21 to limit the position of latching tip 28. The magnetic yoke 26 has a portion thereof formed with a U-shaped cross section at 34 and at the ends of the U there are provided a pair of elongated pole faces 35 which the armature 27 contacts in its attracted position. The yoke 26 and the

spring strip 29 are mounted upon the bimetallic member 21 by means of a rivet 36 so that the legs of the U-shaped portion 34 embrace the bimetallic member so that the yoke 26 is energized magnetically by the current flowing through the bimetallic member 21 which then, in effect, becomes a single turn about the yoke. The armature 27 is mounted by means of the hook end 31 of the spring piece 29 and is disposed with its upper end as viewed in Figure 5, engaging the upper edges of the pole faces 35 of the yoke 26. When the magnetic flux within the yoke is sufficient to attract the armature 27 for movement thereto the armature rotates about its engagement with the edges of the pole face and against the small bias provided by the resilient hook 31. The lower air gap between the armature 27 and the pole faces 35 is determined by a rib 37 within the base (Figure 2) which limits the movement of the armature away from the yoke 26.

In the arrangement herein shown it is seen that for thermal tripping the latching tip 28 moves bodily with the bimetal 21 as it flexes under the heating action of the current passing therethrough. Upon magnetic trip, the latching tip 28 is moved relative to the bimetal 21 by the engagement of the armature 27 with the latching tip to cause movement thereof against its resilient bias. By mounting the armature 27 in engagement with the pole faces 35 of the yoke 26 so as to pivot thereabout, there is provided a small path of low magnetic reluctance which increases the sensitivity of the magnetic trip and lowers the current value at which the armature 27 is attracted to the pole faces of the yoke. With the resilient latching tip only a small magnetic force is required to effect the unlatching movement compared to what would be required to effect movement bodily of the relatively stiff bimetal 21.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

I claim:

1. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke supported upon said bimetallic member and energized in response to the flow of current through the breaker, an armature member also supported upon said bimetallic member and adapted to be attracted to said yoke upon the occurrence of an overload current of sufficient value, and means on said bimetallic member engaging said releasable means and adapted to be moved bodily by said bimetallic member upon flexing thereof in response to the passage of moderate overload currents, said engaging means being movable relative to the bimetallic member by said armature as it is attracted in response to heavy overloads and short circuit currents.

2. In an automatic electric circuit breaker having separable contacts and means releasable to effect separation of said contacts, current responsive means for effecting the release of said

releasable means upon the passage of an overload current through the circuit breaker comprising a bimetallic member heated in response to the flow of current through the breaker, a magnetic yoke supported upon said bimetallic member and energized in response to the flow of current through the breaker, an armature member also supported upon said bimetallic member in engagement with an edge of said yoke and pivoting about said edge into engagement with the yoke as the armature is attracted upon the occurrence of overload currents of sufficient value, and means on said bimetallic member engaging said releasable means and adapted to be moved bodily by said bimetallic member upon flexing thereof in response to the passage of moderate overload currents, said engaging means being movable relative to the bimetallic member by said armature as it is attracted in response to heavy overloads and short circuit currents.

3. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke supported upon said bimetallic member and energized in response to the flow of current through the bimetallic member, an armature member also supported upon said bimetallic member and adapted to be attracted to said yoke upon the occurrence of an overload current of sufficient value, and means engageable with said releasable means to normally latch the same in operative position, said engageable means being moved by said bimetallic member in response to the occurrence of moderate overloads and being moved by said armature member upon the occurrence of heavy overloads and short circuit currents.

4. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a resilient spring strip mounted on said bimetallic member with one end formed as a latching tip to engage said releasable means, a magnetic yoke mounted upon said bimetallic member, an armature member mounted on said bimetallic member for pivotal movement by the opposite end of said resilient strip and maintained thereby in contact with one edge of the magnetic yoke about which edge the armature pivots in moving to attracted position, said yoke and armature engagement providing a path of low magnetic reluctance thereat, the bimetallic member flexing under the action of moderate overloads to bodily move said latching tip out of engagement with said releasable means, said armature moving said latching tip relative to the bimetallic member into releasing position upon the occurrence of heavy overloads and short circuit currents.

5. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a re-

silient spring strip mounted on said bimetallic member with one end formed as a latching tip to engage said releasable means, a magnetic yoke mounted upon said bimetallic member, an armature member mounted on said bimetallic member for pivotal movement by the opposite end of said resilient strip and maintained thereby in contact with one edge of the magnetic yoke about which edge the armature pivots in moving to attracted position, said yoke and armature engagement providing a path of low magnetic reluctance thereat, the resilient spring strip biasing the armature toward unattracted position, and means limiting the extreme unattracted position of the armature, the bimetallic member flexing under the action of moderate overload currents to bodily move said latching tip out of engagement with said releasable means, said armature moving said latching tip relative to the bimetallic member into releasing position upon the occurrence of heavy overload and short circuit currents.

6. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, a resilient spring strip, common means positively supporting said yoke and a midpoint on said strip upon the bimetallic member, one end of said resilient strip being formed as a latching tip engaging said releasable member, an armature member, the opposite end of said resilient strip extending through a slot in said armature member to mount the same upon said bimetallic member with the armature in engagement with an edge of said magnetic yoke about which edge it pivots to rotate to attracted position, the bimetallic member flexing under the action of moderate overload currents to bodily move the latching tip out of engagement with said releasable means, said armature being attracted to the yoke upon the occurrence of heavy overload and short circuit currents and effecting movement of said latching tip relative to the bimetallic member to releasing position.

7. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke, a resilient spring strip, common means positively supporting said yoke and a midpoint on said strip upon the bimetallic member, one end of said resilient strip being formed as a latching tip engaging said releasable member, an armature member, the opposite end of said resilient strip extending through a slot in said armature member to mount the same upon said bimetallic member with the armature in engagement with an edge of said magnetic yoke about which edge it pivots to rotate to attracted position, said opposite end of the resilient strip biasing the armature against the edge of the yoke and into its unattracted position, and means limiting the extreme unattracted position of said armature, the bimetallic member flexing under the action of moderate overload currents to bodily move the latching tip out of engagement with said re-

leasable means, said armature being attracted to the yoke upon the occurrence of heavy overload and short circuit currents and effecting movement of said latching tip relative to the bimetallic member to releasing position.

8. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke supported upon said bimetallic member and energized in response to the flow of current through the breaker, an armature member also supported upon said bimetallic member and adapted to be attracted to said yoke upon the occurrence of an overload current of sufficient value, a resilient strip carrying a latching surface engageable by said releasable means, a main portion of said strip being disposed on the high expansion side of the bimetallic member and having an abutment as the low expansion side of the bimetallic member so that the latching surface and resilient strip are moved bodily by the bimetallic member as it engages the abutment upon flexing in response to the passage of moderate overload currents, said armature moving the latching surface and strip relative to the bimetallic member as the armature is attracted in response to heavy overload and short circuit currents.

9. In an automatic electric circuit breaker having separable contacts and means releasable to effect separation of said contacts, current responsive means for effecting the release of said releasable means upon the passage of an overload current through the circuit breaker comprising a bimetallic member heated in response to the flow of current through the breaker, a magnetic yoke supported upon said bimetallic member and energized in response to the flow of current through the breaker, an armature member also supported upon said bimetallic member and adapted to be attracted to said yoke upon the occurrence of an overload current of sufficient value, and a resilient metallic strip mounted on said bimetallic member and carrying a latching surface engageable by said releasable means, said latching surface and resilient strip being bodily movable by the bimetallic member by flexing thereof in response to the passage of moderate overload currents, said latching surface and strip being movable relative to the bimetallic member by said armature as it is attracted to the yoke in response to heavy overloads and short circuit currents.

10. A circuit breaker including relatively movable contacts, a releasable member operable when released to effect opening of said contacts, trip means including a bimetal element electrically connected to be traversed by current, electroresponsive means comprising a pair of magnetic members on opposite sides of said bimetal element and energized by the current flow therethrough, both of said magnetic members being movable, resilient means movable upon occurrence of overload current flow by said trip means one of said magnetic members being engaged by said resilient means and biased thereby away from said bimetal element but being movable magnetically relative to said bimetal against the bias of said resilient means to effect release of said releasable member upon the occurrence of a heavy overload, and the other magnetic member

being fixedly mounted upon said bimetal element and movable thereby upon bending of said bimetal element to effect release of said releasable member upon the occurrence of a smaller overload.

5 11. In a circuit breaker comprising relatively movable contacts and a releasable member operable when released to effect opening of said contacts, trip means comprising a bimetal element and electroresponsive means, said electroresponsive means comprising a core member and a movable armature surrounding said bimetal element, resilient means movable upon the occurrence of overload current flow by said trip means, said resilient means engaging said armature and biasing said armature away from said bimetal element, said core member being mounted to be moved by said bimetal element, said bimetal element flexing when heated a predetermined amount to move said core member of the electroresponsive means and effect release of said releasable member, and said electroresponsive means being operable to move the armature relative to the core member in response to overload current above a predetermined value to instantaneously effect release of said releasable member.

10 12. In a circuit breaker comprising relatively movable contacts and a member releasable to effect opening of said contacts, a bimetallic member heated by the current of the circuit of the breaker, an electromagnet supported on said bimetallic member, said electromagnet comprising a core member energized by the current flow through said bimetallic member and a movable armature, said bimetallic member flexing when heated a predetermined amount to bodily move said electromagnet and effect release of said releasable member, and said electromagnet being operable in response to overload currents above a predetermined value to instantaneously release the releasable member without substantially moving said bimetallic member.

15 13. In a circuit breaker comprising relatively movable contacts and means releasable to effect opening of said contacts, trip means operable to release said releasable means in response to overload currents comprising an electromagnet having a magnetic core member and a movable armature operable to release said releasable means, a current responsive bimetal element forming the sole support for said core and said armature, said bimetal element flexing when heated a predetermined amount to bodily move said core member and said armature without substantially increasing the gap therebetween to release said releasable means.

20 14. In a circuit breaker comprising relatively movable contacts and operating means therefor, trip means operable in response to overload currents to effect contact opening operation of said operating means, said trip means comprising an electromagnet having a magnetic core member, an armature operable to effect opening operation of said operating means, and a bimetal element connected in the circuit of the breaker to be heated by the current of the circuit and operable when heated a predetermined amount to bodily move said core member and said armature to effect opening operation of said operating means, said bimetal element constituting the sole supporting means for said core member and said armature and being connected to move both said core member and said armature when the bimetal

bends without substantially increasing the gap between the core member and the armature.

15. In a circuit breaker comprising relatively movable contacts and means releasable to effect opening of said contacts, trip means operable in response to overload currents to release said releasable means, said trip means comprising a bimetal element traversed and heated by the current of the circuit, an electromagnetic core member mounted for movement by said bimetal element and extending around three sides of said bimetal element to be energized by current traversing said bimetal element, a movable armature pivotally supported on said electromagnetic core member, said electromagnetic core member being operable in response to overload currents above a predetermined value to attract said armature and effect instantaneous release of said releasable means, and said bimetal element flexing when heated a predetermined amount in response to overload currents below said predetermined value to move said electromagnetic core member and effect release of said releasable means.

16. In a circuit breaker comprising relatively movable contacts and means releasable to effect opening of said contacts, trip means operable to release said releasable means in response to overload currents comprising an electromagnet having a magnetic core and a movable armature operable to release said releasable means, a current responsive bimetal element forming the sole support for said electromagnet and said armature, said bimetal element flexing when heated a predetermined amount to bodily move said electromagnet and said armature while the magnetic air gap remains substantially the same to release said releasable means, and means for adjusting said bimetal element while the magnetic airgap remains the same.

17. A circuit breaker including relatively movable contacts, a releasable member operable when released to effect opening of said contacts, trip means including a bimetal element electrically connected to be traversed by current, electro-responsive means comprising a core member and an armature surrounding said bimetal element and energized by the current flow therethrough, said core member being mounted for movement by said bimetal element upon heating thereof due to overloads and said movement of the bimetal element and core member causing release of said releasable member, and said core member having said armature pivotally mounted on the core member for movement relative thereto magnetically upon the occurrence of heavy overloads to also cause release of said releasable member and opening of said contacts.

18. A circuit breaker including relatively movable contacts, a releasable member operable when released to effect opening of said contacts, trip means including a bimetal element electrically connected to be traversed by current, electroresponsive means comprising a pair of magnetic members on opposite sides of said bimetal element and energized by the current flow therethrough, both of said magnetic members being movable, one of said magnetic members being pivotally mounted on the other magnetic member, a spring biasing said pivotally mounted magnetic member away from the other magnetic member and said pivotally mounted magnetic member being magnetically movable about its pivot against the bias of said spring without bending said bimetal element to effect release of said releasable member upon the flow of a prede-

termined heavy current, and the other magnetic member being movable upon bending of said bimetal member to effect release of said releasable member upon the occurrence of a predetermined smaller current.

19. A circuit breaker including relatively movable contacts, a releasable member operable when released to effect opening of said contacts, a terminal strip, a bimetal element mounted and electrically connected at its upper end to said terminal strip, a flexible conductor connected to the lower end of the bimetal element and electrically connecting it in series with said contacts, a core member having a U-shaped section of magnetic material extending around the bimetal element, an armature extending across and pivoted on the ends of the U of the core member, said core member being movable upon bending of the bimetal element to cause release of said releasable member upon the flow of a predetermined current through the bimetal element, a spring biasing said armature against pivotal movement toward the ends of the U of the core member, and said armature being movable about its pivot against the bias of said spring by the magnetic flux caused in the U-shaped core member and armature by the current flow in the bimetal element to cause release of the releasable member upon the flow of a higher predetermined current through the bimetal element.

20. A circuit breaker including relatively movable contacts, a releasable member operable when released to effect opening of said contacts, trip means including a bimetal element electrically connected to be traversed by current, electro-responsive means comprising a pair of magnetic members mounted on opposite sides of said bimetal element and energized by the current flow therethrough, both of said magnetic members being movable, a strip of spring material having a portion thereof movable to effect release of said releasable member, one of said magnetic members being movable magnetically toward the other magnetic member and causing bending movement of the spring strip against its normal bias to the point where said portion of the spring strip causes release of the releasable member, said other magnetic member being movable upon thermal bending of the bimetal element and said bending of the bimetal element also causing movement of said portion of the spring strip to effect release of the releasable member.

21. In a circuit breaker having relatively movable contacts and means releasable to effect opening of said contacts, current responsive means for effecting release of said releasable means in response to overload currents below a predetermined value comprising a bimetal element, a magnetic member mounted on said bimetal element, a second magnetic member adapted to be attracted by the first said magnetic member in response to overload currents above said predetermined value, a biasing member extending along said bimetal element for supporting said second magnetic member, said bimetal element operating said biasing member in response to overload currents below said predetermined value to effect release of the releasable means and both of said magnetic members being movable upon movement of the bimetal element with the air gap between the two magnetic members remaining substantially constant, and said magnetic members being attracted in response to overload currents above said predetermined value to actu-

ate said biasing member and effect instantaneous release of said releasable means.

22. In a circuit breaker having terminals and contacts, at least one of which contacts is movable, and a spring-actuated trip arm releasable by thermal and magnetic means to cause opening of said circuit contacts, the combination of a bimetal member connected at one point to one of said terminals and at another point to one of said relatively movable contacts so as to carry current therethrough and a magnet and armature mounted on said bimetal member at opposite sides thereof so as to partially surround said bimetal member, spring means pressing said magnet and armature apart so as to establish a magnet air-gap, said armature being movable by and with said bimetal member on the occurrence of relatively small overloads, and movable by said magnet independently of and relative to said bimetal member on the occurrence of relatively large overloads to cause release of said trip arm, said magnet air-gap remaining substantially unaltered during movement of said armature by and with said bimetal member.
